CLAIM

The ornamental design for a combined collapsible cup, compass and altimeter, as shown and described.

DESCRIPTION

FIG. 1 is a front elevational view of a combined collapsible cup, compass and altimeter showing my new design with the cup collapsed;

FIG. 2 is a top plan view;

FIG. 3 is a bottom plan view;

FIG. 4 is a sectional view, taken along line 4—4 of FIG. 1, with the cup shown collapsed; and

FIG. 5 is an exploded top front perspective view thereof.
